UNITED STATES PATENT OFFICE.

FREDERICK L. SCHMALZ, OF ST. PAUL, MINNESOTA.

DESIGN FOR A WATCH-CHARM OR SIMILAR ARTICLE.

SPECIFICATION forming part of Design No. 36,497, dated August 18, 1903.

Application filed June 22, 1903. Serial No. 162,684. Term of patent 14 years.

To all whom it may concern:

Be it known that I, FREDERICK L. SCHMALZ, a citizen of the United States, residing at St. Paul, in the county of Ramsey and State of Minnesota, have invented a new, original, and ornamental Design for a Watch-Charms or a Similar Article, of which the following is a specification, reference being had to the accompanying drawings, forming part thereof.

Figure 1 is a face view of a watch-charm, showing my new design. Fig. 2 is a reverse view of Fig. 1.

What I claim as new, and desire to protect by Letters Patent, is—

The ornamental design for a watch-charm or similar article, as shown.

In testimony whereof I have signed my name to this specification in the presence of two subscribing witnesses.

FREDERICK L. SCHMALZ.
